UNITED STATES PATENT OFFICE.

FRANK L. CROSBY, OF FARMER CITY, ILLINOIS.

HAME.

SPECIFICATION forming part of Letters Patent No. 415,028, dated November 12, 1889.

Application filed July 23, 1889. Serial No. 318,447. (No model.)

To all whom it may concern:

Be it known that I, FRANK L. CROSBY, of Farmer City, in the county of De Witt and State of Illinois, have invented certain new and useful Improvements in Hames; and I do hereby declare the following to be a full, clear, and exact description of the invention, such as will enable others skilled in the art to which it pertains to make and use it, reference being had to the accompanying drawings, which form part of this specification.

My invention relates to an improvement in hames; and it consists in a hame provided with a slot or opening through it with the endwise moving and sliding tug, which is provided with a spring-catch for locking the tug in position, as will be more fully described hereinafter.

The object of my invention is to so construct the hame and the tug that the tug can be adjusted vertically upon the hame, according to the height of the draft desired, and then locked rigidly in position.

Figure 1 is a side elevation of a hame which embodies my invention. Figs. 2 and 3 are edge views of the same. Fig. 4 is a perspective of the tug.

A represents the hame through which the slot or opening B is made. This slot will be made of a length proportioned to the distance that the tug is to be adjusted, and just wide enough to allow the tug to be moved back and forth therein. Applied to the outer edge of the hame is the metallic plate C, which also has a slot or opening made through it corresponding to the opening in the tug, and in one edge of the slot are made a number of recesses D, which are placed at equal distances apart, and in which the spring locking devices 40 catch for the purpose of holding the tug in any desired position. Applied to the inner edge of the hame, when it is made of wood, is the metallic block or casting G, which is also provided with an opening through it corresponding to the slot B through the hame, and in opposite edges of which are formed the recesses I, in which the shoulders J on the inner end of the tug L catch. This tug is shaped as shown in Fig. 4, and to which the spring-

catch or locking device O is secured. In the 50 side of the tug just under the spring-catch is made a sufficient recess or opening to allow the catch a suitable amount of play for the purpose of allowing the outer free end of the catch to be forced inward when it is desired to loosen the 55 tug for the purpose of adjusting it from one position to another. The front end of the tug is made sufficiently thick so that it cannot be drawn through the slot either in the metallic block or in the hame, and upon opposite 60 sides of this end are formed the shoulders J, which catch in the notches or recesses formed in the metallic block to receive them at the same time that the spring-snap catches in the recesses in the metallic plate. When the tug 65 is to be changed from one position to another, the outer end of the spring-catch is depressed, so as to free it from the recess in which it is locked, and then the tug is forced endwise through the slot in the hame until the shoul- 70 ders J are freed from the notches or recesses, and then the tug is moved either up or down in the slot, as may be desired. After the tug has been moved into position pressure is applied to its front end and then it is 75 forced backward through the slot until the spring-catch snaps into a recess in the plate C, when the tug will again be locked in position. The shoulders J prevent any movement of the tug at its front end, and the 80 spring-snap prevents any at its rear end, and hence the tug is held rigidly in the position into which it may be adjusted.

By means of the construction here shown and described the tug can be adjusted upon 85 the hame so as to accommodate the draft to any desired height.

Having thus described my invention, I claim—

1. The combination, with a hame provided 90 with a slot B, which extends entirely through it, a slotted metallic plate C, which is attached to the outer edge of the hame and provided with notches D, and a slotted metallic plate or casting G, secured to the inner edge of the 95 hame and provided with the notches or recesses I, of the vertically-movable tug, which extends through the slot and is provided with

the shoulders J at its inner end, and the spring-catch O, substantially as shown.

2. The combination of the hame provided with a slot, a metallic plate applied to the edge of the hame and provided with recesses for the spring-snap to catch in, a metallic block applied to the inner edge of the hame, and also provided with recesses, with the tug which is adjustable back and forth in the slot

and provided with shoulders at one end, and a spring-snap, substantially as described.

In testimony whereof I affix my signature in presence of two witnesses.

FRANK L. CROSBY.
